UNITED STATES PATENT OFFICE.

CHARLES P. QUINLIN, OF DENVER, COLORADO.

ROAD CONSTRUCTION.

1,281,833.

Specification of Letters Patent.

Patented Oct. 15, 1918.

Application filed October 17, 1917. Serial No. 197,041.

To all whom it may concern:

Be it known that I, CHARLES P. QUINLIN, a citizen of the United States, residing at the city and county of Denver and State of Colorado, have invented certain new and useful Improvements in Road Construction; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 The object of this invention is to provide a road construction whereby a graded earth road may be rendered serviceable for travel in bad weather without requiring the surfacing of the entire road bed with asphalt, 20 macadam or the like.

Another object to consider is the provision of a comparatively cheap road construction for the purpose above indicated, at least a part of the materials of which may be removed and used elsewhere in road construction when the community in which the materials were originally used becomes more prosperous and it is decided to construct a better road.

30 Briefly stated, the invention consists in embedding in a graded road bed series of square blocks of suitable length, the faces of the blocks being flush with the road surface and forming parallel tracks for the 35 wheels of vehicles. These blocks are termed "road rails." The object in using square blocks is that when the exposed face of a block becomes damaged or badly worn, the block may be taken up, the damaged portion repaired if there is one and the block replaced with another face exposed. While in good weather the entire road may be used, in bad weather the tracks or rails furnish a 40 solid wheel surface and at the same time save the earth bed from wheel cuts.

45 Referring to the drawings

Figure 1 shows the road in perspective and indicates the cross sectional construction;

Fig. 2 indicates one manner of positioning the blocks and connecting them with ties;

Fig. 3 illustrates a form of tie that may be used;

Fig. 4 indicates the construction at a curve;

Fig. 5 shows one form of block in cross section;

Fig. 6 shows another form of block in cross section, and together with Fig. 5 indicates the manner of laying the blocks and 60 one form of construction that may be used between the rails or tracks; and

Fig. 7 shows the manner of flushing the space between the abutting ends of the blocks, being taken on line 7—7 of Fig. 2.

The rails or blocks 2 are formed preferably of cement concrete, but may be of asphaltic concrete, mineral slag, burnt clay or any other suitable mixture, and are reinforced with woven wire 3 or the like. If 70 desired the surfaces of the blocks may be roughened as by troweling. The blocks being square in cross section four wearing surfaces of equal extent are provided. Also the blocks are of uniform length so that they 75 may be interchanged or a new one substituted when necessary. The blocks are about one foot square and five feet long which affords bottom surface sufficient to enable them to retain their position when laid.

80 Preferably the blocks are laid on a gravel base or section 4, but they may be laid directly on the earth bed, and are so arranged that the joints are offset or staggered as shown in Fig. 2. Ties 5 may be 85 used to secure the blocks against lateral displacement, oppositely disposed fingers 6 on each end of each tie fitting into recesses 7 in the ends of the blocks. When so laid the joints are flushed with asphalt or other suitable material 8, this flushing also aiding in anchoring the ends of the blocks.

85 For ordinary graded roads a satisfactory drainage for the middle of the road may be obtained by ditching as shown, laying tile 9 95 with the sections slightly separated, laterals being provided at suitable points, and filling in with a gravel or sandy soil 10. Washing away of the crown of the road is thus avoided.

100 A desirable construction which would obviate the necessity of underground drainage is shown in Figs. 5 and 6, a strip 12 of asphaltic or like pavement being laid between the rails and flush therewith, thus shedding 105 water to the outside of the rails.

At curves short blocks 13 are used in order to avoid molding curved blocks of greater length, only two sides of which could ever be used as wearing surfaces, and 5 then at the same curvature points only.

In Fig. 6 a block is shown having a reinforced core 15 of concrete or like material, with an asphaltic facing 16 on each side thereof. This would provide a more resili- 10 ent tread and would be particularly desirable when the asphaltic strip 12 is used between the rails.

If desired the blocks could be slightly concave on each face in order to guard some- 15 what against skidding, but this must necessarily be very slight in order that the overhang would not be appreciable and thereby weaken the edges of the blocks.

One pair of rails is shown but, obviously, 20 two pairs could be used to care for traffic in opposite directions.

Where some drainage is required but it is not desired to use tile 9, the blocks may be molded with a passage 17 as shown in Figs. 25 5 and 6. In this case the asphalt flushing 8 would fill only the top of the joint so as not to clog the passage 17. This drainage feature could be used to advantage in connection with the asphalt paving strip 12, or 30 alone, or as an auxiliary to the tile as shown in Fig. 1. In this form the tie recesses 7 would be below the passage 17. Drainage laterals would be provided at suitable points.

My invention offers many advantages for 35 country roads and those in other communities where the cost of construction of roads fully surfaced with asphalt or like material is prohibitive.

In the first place the initial cost is less, 40 with the added advantage that the rails may be turned over to expose a new surface whenever an old surface is damaged or badly worn.

Moreover the invention aids in maintaining 45 the crown of the road against washing,

in addition to maintaining the longitudinal and horizontal grade or survey lines of such roads.

Because of this maintenance of the crown of the roads they can be constructed at a 50 cost not exceeding what is now wasted in the continual process of re-grading and re-building the road crown. Even where the asphalt-faced blocks and the strip of asphalt pavement are used the expense would 55 still be within that of present road construction and maintenance.

What I claim is:

1. Road construction comprising parallel road rails all of the faces being of approxi- 60 mately the same width, whereby each face may be used as a wearing surface in turn embedded in the road bed with the upper faces of the rails flush with the road surface.

2. Road construction comprising parallel road rails embedded in the road bed with the upper faces of the rails flush with the 65 road surface, the rails being square in cross section whereby each face may be used as a wearing surface in turn.

3. Road construction comprising parallel series of road rails embedded in the road, the rails in each series being arranged end to end, said rails being square in cross section and of uniform length, whereby the 70 rails may be used interchangeably and any one of the four faces may be exposed as the wearing face.

4. Road construction comprising parallel series of road rails embedded in the road 80 with their upper faces exposed, the road being ditched between the rails, drainage means therein and the ditched portion being filled with porous material, the rails in each series being arranged end to end and 85 having longitudinal drainage passages therethrough.

In testimony whereof I affix my signature.

CHARLES P. QUINLIN.
